John Bolton 917X

Aug 2, 1808

Letter Patent → U.S. Cl. 3, 1808.

The subject of this is in these Letter Patent and making part of the same
containing a description in the words of the said John Bolton himself of his
Invention.

The blanching machine is to be worked by a lever this lever to play in a roller
and in this roller is a slot eight inches in length and on the lower end of this
a semi or quarter circle on which are to be prepared eggs on the face, and the
eggs on this semi or quarter circle to wash into a funnel like on the top of a
wheel or dexter which dexter works in the body of the churn which churn may
be either round or square - the drive lever may be applied to a wheel which
is worked on the face similar to the above mentioned circle and may operate in two
wheel or one as the case may require - These wheels are to stand in a perpendicular
form and may be fitted with arms to project through the staff of this wheel
and on the end of these arms are to be fixed flats in a perpendicular form like
the staff.

Witness,

(sgd) William Thornton,
(sgd) George Adams,

(sgd) John Bolton
